UNITED STATES PATENT OFFICE

172,999

DINNER PLATE OR SIMILAR ARTICLE

Michael J. Szymanski, Syracuse, N. Y., assignor to Onondaga Pottery Company, Syracuse, N. Y., a corporation of New York

Application April 24, 1953, Serial No. 24,652

Term of patent 14 years

(Cl. D44—15)

To all whom it may concern:

Be it known that I, Michael J. Szymanski, a citizen of the United States, residing at Syracuse, State of New York, have invented a new, original, and ornamental Design for a Dinner Plate or Similar Article, of which the following is a specification, reference being had to the accompanying drawing, forming part hereof.

The drawing is a plan view of a dinner plate of conventional configuration showing my new design.

I claim:

The ornamental design for a dinner plate or similar article, as shown and described.
